(57) **CLAIM**

The ornamental design for a display screen with virtual three-dimensional icon or display system with virtual three-dimensional icon, as shown and described.

DESCRIPTION

FIG. 1 is a front view of a display screen with virtual three-dimensional icon in which the icon is shown in a perspective orientation;

FIG. 2 is another front view thereof, showing a front orientation thereof;

FIG. 3 is another front view thereof, showing a rear orientation thereof;

FIG. 4 is another front view thereof, showing a side orientation thereof;

FIG. 5 is another front view thereof, showing an opposite side orientation thereof;

FIG. 6 is another front view thereof, showing a top orientation thereof;

FIG. 7 is another front view thereof, showing a bottom orientation thereof;

FIG. 8 is a front view of a display system with virtual three-dimensional icon shown in a perspective orientation, the virtual three-dimensional icon being the same design as shown in the first embodiment of FIGS. 1-7;

FIG. 9 is another front view thereof, showing a front orientation thereof;

FIG. 10 is another front view thereof, showing a rear orientation thereof;

FIG. 11 is another front view thereof, showing a side orientation thereof;

FIG. 12 is another front view thereof, showing an opposite side orientation thereof;

FIG. 13 is another front view thereof, showing a top orientation thereof; and,

FIG. 14 is another front view thereof, showing a bottom orientation thereof.

The broken lines showing the triangular-shaped region on the bottom of the icon and the icon interior form no part of the claimed design. In FIGS. 1-7, the outermost broken line represents a display screen which forms no part of the
